PHOTOGRAPHIC REVERSAL PROCESS USING HIGH-INTENSITY FLASH EXPOSURE

Gerald I. P. Levenson, Wealdstone, England, assignor to Eastman Kodak Company, Rochester, N. Y., a corporation of New Jersey

No Drawing. Application February 1, 1950, Serial No. 141,833. In Great Britain February 14, 1949

2 Claims. (Cl. 95—5)

1

This invention relates to photographic processes and especially to photographic reversal processes.

In Knott and Stevens U. S. Patent 2,456,953, there is described a method of producing reversed photographic images which comprises exposing to an object or an image, a sensitive silver halide emulsion layer comprising a silver halide emulsion of the type therein defined, then without developing the latent image so formed to a visible image treating the emulsion to render it capable of forming surface latent image, and then subjecting it directly (i. e. not through a negative or positive image) to an exposure of sufficient intensity and time to cause a reversed image to develop by treating it in a developer which will develop surface latent image but not develop or develop only slightly the first formed internal latent image.

The silver halide emulsion is defined in the Knott and Stevens patent as being of such a nature that the latent image is formed mostly inside the silver halide grains and relatively little surface latent image is formed. Emulsions of this type are also described in Davey and Knott U. S. application Serial No. 82,914, filed March 22, 1949.

Many emulsions of this type when coated on a support and used to make a direct positive image by the methods described in Knott and Stevens U. S. Patent 2,456,953 by giving an image-wise exposure of the order of $1/25$ of a second or longer followed by a second exposure sufficiently long to obtain good contrast in the reversed image yield an image which is degraded by a comparatively heavy veil and this is particularly undesirable when the emulsion is coated on paper and the resultant light-sensitive material is used for document copying.

It is therefore an object of the present invention to provide a method for making an improved direct positive photographic image. A further object is to provide an improvement in or modification of the invention described in Knott and Stevens 2,456,953.

These objects are accomplished according to the present invention by making the first or image-wise exposure in an emulsion of the internal latent image type as described in the Knott and Stevens patent, of a duration of $1/10,000$ of a second or less. Such exposure may be made by using a high intensity light equivalent in intensity to a gas discharge lamp, for example, a

2

Kodatron Speedlamp which provides an extremely high intensity flash of the order of $1/10,000$ of a second or less in duration.

For example, two of these lamps, used together and provided with suitable reflectors, were used to illuminate a 10" x 8" document having a clean white background, in an optical printer for making a fullscale reproduction. A light-sensitive material was used containing a layer of emulsion as defined above which gave a reversed image of a gamma of 0.6 and a veil having a reflection density of 0.25 when the first exposure was about 30 seconds with an ordinary tungsten lamp. When using the two "Kodatron" lamps according to the invention, the reversed image had a gamma of 1.4 with a veil having a reflection density of 0.05.

The emulsion which I use in the present invention is of the type in which the latent image is formed mostly or entirely internally in the grains; that is to say an emulsion only few or none of whose exposed grains are developable to silver by a developing solution which cannot act as a developer for latent image inside the grains—such a solution is Formula I (below). Whether an emulsion is of this type for the purpose of this invention can be ascertained by treating it (after exposure) in developers of the kind given in Formulae I, II and III below. It is of the type defined if it will develop in those of Formula II but will not develop or will develop only slightly in Formula III and in Formula I.

The developer formulae above referred to are:

FORMULA I

"Surface" developer

p-Hydroxyphenylglycine	grams	10
Sodium carbonate (cryst.)	do	100
Water to	cc	1,000

40 Development time 4 minutes at 20° C.

FORMULA II

"Internal" developer

45 Hydroquinone	grams	15
N-methyl-p-aminophenyl sulphate	do	15
Sodium sulphite, anhy	do	50
Potassium bromide	do	10
Sodium hydroxide	do	25
Sodium thiosulphate (cryst.)	do	20
Water to	cc	1,000

Development time 3 minutes at 20° C.

3

FORMULA III

Commercial Developer

Hydroquinone	grams	12
N-methyl-p-aminophenol sulphate	do	3
Sodium sulphite (cryst.)	do	90
Potassium bromide	do	4
Sodium carbonate (cryst.)		150
Water to	cc	1,000

Development time 4 minutes at 20° C.

As measured according to normal photographic testing technique, when a test layer of the emulsion is coated on a transparent support, for example glass, and the layer is exposed for a fixed time between $\frac{1}{100}$ and one second to a light intensity scale which gives upon full development at 20° C. in the internal developer Formula II a transmitted density which is the arithmetic mean of the densities obtainable by varying only said intensity, the transmitted density so obtained is at least five times the transmitted density obtained when an identical test layer of the emulsion is exposed for the same length of time to light of the same intensity and fully developed at 20° C. in the surface developer Formula I or preferably Formula III.

A further advantage of the use of an exposure of extremely brief duration is that loss of definition due to vibration in the camera is avoided, so that the camera may be made of a lighter construction than has hitherto been found necessary.

It will be understood that my invention is to be taken as limited only by the scope of the appended claims.

I claim:

1. The method of producing a reversed photographic image, which comprises exposing to a lighted object or image, for a period not exceeding 0.001 second, with a high intensity light equal in intensity to a gas discharge lamp, a layer of a light-sensitive silver halide emulsion, a test layer of which, when coated on a support and the layer exposed to a light intensity scale for a fixed time between $\frac{1}{100}$ and one second, gives upon full development at 20° C. in the following developer (II):

Hydroquinone	grams	15
N-methyl-p-aminophenol sulfate	do	15

4	Sodium sulfite, anhydrous	grams	50
	Potassium bromide	do	10
	Sodium hydroxide	do	25
	Sodium thiosulfate, crystals	do	20
	Water to	cc	1,000
10	a transmitted density which is the arithmetic mean of the minimum and maximum densities obtainable by varying only said intensity, which density is at least five times the transmitted density obtained when an identical test layer of the emulsion is exposed for the same length of time to light of the same intensity and fully developed at 20° C. in the following developer (I):		
15	p-Hydroxyphenyl glycine	grams	10
	Sodium carbonate, crystals	do	100
	Water to	cc	1,000
20	soaking the exposed emulsion layer in a photographic developer which develops substantially only the latent image which is developable by the following developer (III):		
25	Hydroquinone	grams	12
	N-methyl-p-aminophenol sulfate	do	3
	Sodium sulfite, crystals	do	90
	Potassium bromide	do	4
	Sodium carbonate, crystals	do	150
	Water to	cc	1,000
30	for a length of time sufficient to give no more than a negligible development of the latent image but sufficient to render the emulsion layer capable of forming surface latent image which is developable by the aforesaid developer (III), and then subjecting the emulsion layer to a uniform exposure to light to produce latent image, some of which is developable by the aforesaid developer (III), and then developing the emulsion layer in a developer which develops the latent image which is developable by said developer (III) and gives no more than a negligible development of the negative latent image formed by the original exposure compared with the positive image which is developed.		
35	40		
45	2. The method of claim 1, in which the high intensity light is a high intensity gas discharge flash.		

GERALD I. P. LEVENSON.
